UNITED STATES PATENT OFFICE.

MOTOI FUJIURA, OF LOS ANGELES, CALIFORNIA.

COMBINATION FAN, COMPRESSOR, AND MOTOR-STARTER.

1,333,753.

Specification of Letters Patent. Patented Mar. 16, 1920.

Application filed September 4, 1918. Serial No. 252,533.

To all whom it may concern:

Be it known that I, Motoi FUJIURA, a subject of the Emperor of Japan, residing at Los Angeles, in the county of Los Angeles and State of California, have invented a new and useful Combination Fan, Compressor, and Motor- Starter, of which the following is a specification.

This invention relates to a new and useful motor starting device for automobiles, and for all explosive and internal combustion motors.

This invention has for its object the provision of compactly arranged mechanism, by the use of which the operation of starting an explosive or combustion engine will be performed automatically, and by which a supply of air under pressure which may be used for inflation of tires, or for cooling the engine, may be automatically maintained.

In carrying out this invention the starting and compression mechanism have been incorporated with the fan which is provided for cooling purposes, and a principal object of the invention is to provide a compact, effective, readily controlled, and light weight mechanism adapted for effecting a fluid pressure and for starting the engine or combustion motor independently of manual labor.

The above and other objects will become apparent in the following description, which refers to the drawings, and the essential characteristics are summarized in the claims.

Upon the annexed drawings, Figure 1 is an end elevation of a fluid compressing and motor starting apparatus embodying my invention. Fig. 2 is a perspective detail view of a rocker which is adapted to actuate a piston. Fig. 3 is a perspective detail view of a link adapted to connect the rocker and a piston. Fig. 4 is a perspective detail view of the control valve actuator. Fig. 5 is a top plan view of the yoke which supports the inner clutch member. Fig. 6 is a vertical and sectional view of the device. Fig. 7 is a sectional detail view of the automatic pressure regulating valve which controls the valve actuator. Fig. 8 is a plan view of the planetary gearing by which motion is transmitted to the annular piston chamber. Fig. 9 is a side elevation of the internal gear member of the planetary gear set. Fig. 10 is a perspective view of a piston with link attached. Fig. 11 is an end elevation of the revoluble compressor elements. Fig. 12 is

a fragmentary view of the outer compressor member showing the valve chamber therein. Fig. 13 is a perspective view of the valve controlling the compression chamber. Fig. 14 is a side elevation of the valve. Fig. 15 is a top plan view of the device. Fig. 16 is a fragmentary and sectional detail view showing the inner clutch and driving sprocket. Fig. 17 is a detail view showing the spring which automatically actuates the valve controlling the fluid pressure. Fig. 18 is a detail view showing the spring which actuates the ratchet pawl. Fig. 19 is a sectional detail view of the pressure cylinder which actuates the brake.

Assuming the invention to be embodied as illustrated, the compressing and motor starting apparatus comprises bracket supporting member 21, adapted to be secured to a combustion engine (not shown), and provided with an integral stud or axle member 22, having ball bearings 24, and supporting the revoluble driving member 23, which is provided with a fixed and synchronously rotat- 75 ing sprocket gear 25, adapted to be connected to the engine shaft (not shown). The outer compressor member 26 has an annular piston chamber 27, of semicircular section, and extending approximately around the compressor member; being terminated by fixed abutment 28, and provided with annular flanges 29 and brake rim 30. Member 26 further includes the integral hub 31 and radial spokes 32, 33, and is revolubly sup- 80 ported by ball bearing members 34, on mem- 90 ber 23. Hub 31 has a segmental chamber 35, and spoke 33 has a communicating duct 36, extending to port 37 in valve chamber 38. Cams 39 and 40, project from hub 31; their 95 function being hereinafter noted. As shown in Fig. 12, port 41 forms communication be- 100 tween valve chamber 38 and piston chamber 27. Port 42 is a port of admission to cham- 105 ber 27. Port 43 serves for exhaust of pres- 110 sure from chamber 27. Port 44 serves for transmission of the fluid pressure to the aux- 115 iliary valve chamber 45, and port 46 serves for transmission of fluid pressure from chamber 45 to chamber 38, as hereinafter noted. The spaced apart brake rim 30 is supported by web sections 47.

The inner revoluble compressing member 48, consists of an annular rim 49, provided with oppositely disposed abutments 50 and 110 oppositely disposed ears 51, and further pro- 115 vided with annular compression rings 52.

abutting against flanges 29, of the outer compressor member. The rim 49 is supported by two oppositely disposed spokes 53, integral with hub 54, on which is mounted the engine fan 55.

Rockers 56, are pivotally secured to ears 51, and have angularly disposed short arms 57, and long arms 58. The pistons 59, provided on the outer edge with packings 60, actuated by springs 61, are slidably mounted in the abutments 50, and are connected by links 62, with the long arms 58, of rockers 56. The rockers are normally maintained in operative position by springs 63, to cause the pistons 59 to abut against the walls of piston chamber 27. The cam 39 is in fixed relation to abutment 28, and the rockers are provided with rollers 64, on the shorter arms 57, which engage with cam 39, and actuate the rockers and thereby move the pistons 59 in passing said abutment 28. On passing said abutment, the rollers 65, on the longer arms of the rockers, will engage with cam 40, and thereby return the pistons to operative position; the pistons being then maintained in position by centrifugal force and the action of springs 63. Grease cups 66 are provided for lubrication of the pistons 59 and packings 60.

Referring to Figs. 6, 11, 12, 13, and 14, an oscillating valve 67 is mounted in chamber 38; the valve having a compartment 68 open to the atmosphere, and an inner compartment 69. In the air compressing position, port 70 registers with port 42, allowing the air to enter the piston chamber 27. The pistons within the chamber then compress the air, and, port 42 being closed by the valve, the compressed air passes through port 44 into chamber 45, and thence through the spring-actuated valve 71, and port 46, into the inner compartment 69, which is provided with a port 72, registering with port 37, through which the compressed fluid passes to duct 36 and the segmental grooved chamber 35.

To utilize the compressed fluid for rotating member 48, the valve 67 is reversed as shown in Figs. 1 and 6, with port 72 registering with port 37; the compressed fluid passing through said ports, and thence through port 73 registering with port 41, and acting upon pistons 59, finally exhausting through ports 43 and 70, into compartment 68.

The independent internal gear member 75 intermeshes with pinions 76, mounted on studs 77 projecting from member 23. Member 75 is provided with ratchets 78 and 79, adapted to engage with corresponding ratchets in hub 31, of member 26, and ratchets in member 48. When member 23 is actuated by the motor, gear member 75 will be forced from engagement with member 26, and into engagement with member 48. In this po-

sition, pinions 76, intermeshing with gear member 75 and fixed pinion 74 on member 48, are locked against rotation upon their axial bearing studs 77, thereby effecting synchronous rotation of members 23, 48, 70 and fan 55. Member 75, being lighter than member 26, will be automatically shifted by the turning movement of member 23.

In starting the motor, member 26 is kept from rotating, as hereinafter shown, and member 48 is actuated by the fluid pressure. The turning movement of member 48 forces the gear member 75 into engagement with the relatively stationary member 26, which prevents rotation of member 75. The pinions 76, being driven by pinion 74 fixed to member 48, will run around the internal gear member 75, causing member 23 to rotate, and thereby effecting rotation of the motor. The gear ratios of pinions 74, 76, 85 and internal gear member 75, is such, that effective speed of rotation is transmitted to member 23.

A pressure retaining member 80, in abutment 28, is yieldingly forced into engagement with member 48, by a spring 81, preventing leakage from one portion to another of chamber 27.

A yoke 82 is secured by a nut 83, to supporting member 21. A conical member 84, 95 provided with an annular chamber 85, is rotatively mounted on sleeve member 86, which is provided with a spiral flange 87 in engagement with member 84. Upon rotating member 84 in one direction, the chamber 85 will register with the segmental chamber 35, of member 26. The tube 88, which is fixed to member 84 is thus placed in communication with duct 36, and is adapted to transmit the compressed fluid 105 to and from chamber 27.

Assuming that a tank or other source of compressed fluid (not shown), is in communication with the tubular member 89, the pressure will pass through port 90, in valve 110 91, and thence through a tube 92, to a valve chamber 93, first forcing the piston 94 and piston rod 95 outward, thereby operating the crosshead 96, and through link 97, operating the tube 88, and member 84, to 115 the position shown in Fig. 1, which places the valve chamber 93, through a flexible tube 98, in communication with the tube 88, and the continuous passage formed by chamber 85, the segmental chamber 35, and duct 36, with port 37, in valve chamber 38. Simultaneously with this operation, the outwardly moving crosshead has, through link 99, and lever 100, actuated the brake band 101 to operative position. This prevents rotation of the outer compressor member 26. The inner rotary member, being free to revolve independently, will be actuated by the pressure, and as previously shown, this independent rotation is employed to actuate 130

the motor or combustion engine through the sprocket gear 25, which is driven at a reduced speed as shown.

Means for placing the valves 91 and 67 in the position as described for starting the motor, consist of a manually actuated lever 102, which may be connected in any manner (not shown) to be operated from the driver's seat position, and moved downward in a vertical direction. The downward movement of lever 102, will, through link 103, actuate the yoke 104 with a limited oscillative movement to the position shown in Fig. 1. As shown in Fig. 16, the yoke 104 is connected to a ratchet wheel 105 having a similar movement. A pawl 106, pivotally connected to a link 107, and actuated by a spring 108, is in engagement with ratchet wheel 105, and, upon movement thereof, link 107, pivotally connected to a rocker 109, which in turn is connected by link 110 to valve lever 111, serves to actuate the valve 67 to the position shown in Fig. 1.

Lever 102 is provided with cam 112 adapted to engage with lug 113 on rock-lever 114, connected by links 115, 116, 117, with lever 118, which actuates the valve 91 to the position shown, upon downward movement of lever 102.

The compressed fluid constantly within tube 119 and chamber 120, acts against piston 121 in opposition to spring 122, interposed between valve housing 123 and collar 124 on piston rod 125, which actuates cross-head 126. When the pressure falls below the normal as in starting the engine, spring 122 will force the cross head downward causing cam 127 to engage with cam 128, on link 116. Rock-lever 114 is pivotally connected to pin 129 fixed to lever 130, which is pivotally connected to a fixed arm 131, on valve casing 132. A lever 133 is also pivotally connected to pivotal pin 129, and is provided with a fixed pin 134 in engagement with slot 135 in member 114. A spring 136 connects links 137 and 138, pivotally connected, respectively, to arm 131, and lever 133. The cam 127, on the cross-head, tends to retain rock-lever 114 against the tension of spring 136.

Immediately on release of lever 102 by the operator, a spring 139 having its free ends bearing, respectively, against support 142 and rocker 109, will, through link 110 and lever 111, actuate valve 67 to the reverse position which is hereinbefore described for compressing air, and as the pressure is restored in chamber 120, the piston 121 and crosshead 126 will be forced upward. The oscillative tappet 140, on crosshead 126, engages with pin 134, on lever 133, forcing said lever 133 upward until the angle between levers 133 and 130 is less than 180°, when the tension of spring 136 will cause member 114 to move downward vertically

to release cam 128 from engagement with cam 127, on the crosshead. Upon release from the crosshead, the member 114, actuated by the spring 136 and lever 133, will through the connecting links, actuate valve 91, and close port 90.

Upon closing port 90, ports 141 are opened. This will allow the pressure to escape from tube 92, valve chamber 93, and the flexible tube 98. Upon release of the pressure, the crosshead 96 will move inward, and through link 99 and lever 100, will place the brake band 101 in loose and inoperative position; and, through link 97, operate the tube 88 and member 84 to released position 80 as shown in Fig. 16. Thereupon member 26 will revolve in unison with the inner compressor member 48. In this position, the ratchet pawl 106 will run loosely upon ratchet wheel 105 which is relatively stationary.

Should the pressure at any time fall below the pressure of spring 122, the crosshead 126 is thereupon forced downward by the spring, and is provided with an oscillating tappet 90 141, adapted to engage with pin 134, on lever 133. Pin 134 then will operate member 114, and thereby turn the valve to the position as shown in Fig. 1. The compressed fluid then passes to valve chamber 93, serving to operate crosshead 96 outward, which will constrict the brake band and prevent rotation of member 26. The valve 67, being normally in position for effecting the compression of air, and the member 84 having been operated to connect the segmental chamber 35 and annular chamber 85, by the movement of crosshead 96 outward, the function of compression will be performed during the independent revolution of member 48, as hereinbefore described.

From the foregoing it may be seen that the working of the engine will serve to operate the fan 55, and the apparatus connected thereto will automatically perform the function of compression to replenish the reserve of compressed fluid in the source of supply and the pressure chambers 89, 120, and connecting tube 119. When the pressure becomes greater than the resistance of spring 122, the member 26 will be released and will rotate in unison with the inner compressor member 48. If the engine is at rest, manually operated releasing means for the compressed fluid are provided, and, while held by the operator in released position, the pressure may be employed to start the engine, the same apparatus being utilized to perform the function of an air motor to drive the engine. The apparatus provided will thus serve both as an air compressor and as an air motor, and is believed to be the first arrangement in which these functions are combined. The two independently revolu- 130

ble and annular members are light in weight, and are adapted to be mounted in the space and position usually occupied by the fan of an internal combustion engine. The change 5 from an air motor to a compressor is automatically accomplished by a spring 139, acting against the rocker 109, and its support 142, which is fixed to member 26. During the revolution of member 26, the pawl 106, 10 and link 107, would tend to fly outward, but are retained in operative position relative to the ratchet wheel 105, by a fixed member 143, projecting from member 26, and limiting the outward movement.

15 From the foregoing description and drawings, it is believed that the operation of the device will be understood without further explanation.

What is claimed is:

20 1. A compressor comprising an outer revoluble member forming an annular fluid compressing chamber, an abutment forming the ends of the chamber, an inner revoluble member forming the inner wall of the compressing chamber, abutments on said inner revoluble member, pistons working in said abutments on the inner member, rockers to actuate said pistons, oppositely disposed ears on the inner member to which the rockers 25 are pivotally connected, a hub integral with the outer member, cams on the hub to actuate said rockers to pass the abutment forming the ends of the compressing chamber, a valve in the said abutment serving to open 30 and close ports of communication in the compressing chamber, and brake means to stop the movement of the outer revoluble member.

40 2. The combination with two independently revoluble members forming an annular and segmental fluid compressing chamber, of pistons projecting from one revoluble member and working in said annular chamber, means for retarding the outer member 45 to effect the compression within the chamber, valve means for entrapping the compressed fluid, and means for conveying the compressed fluid to the source of supply.

50 3. The combination with independently revoluble outer and inner members forming an annular and segmental compressing chamber, of an abutment integral with the outer member and projecting into the compressing chamber, pistons radially mounted 55 in the inner member and projecting into the compressing chamber, means for retracting the pistons to pass the abutment, valve means in the abutment for entrapping the compressed fluid and control of the intake and exhaust of the same to and from the compressing chamber, and means for retarding the movement of the outer member.

60 4. The combination with independently revoluble outer and inner members disposed 65 to form an annular segmental compressing

chamber, of a fixed abutment on the outer member determining the ends of the compressing chamber, a valve in the abutment having a plurality of ports adapted for communication with the compressing chamber, 70 a plurality of pistons radially mounted in said inner member, and working in said chamber, a hub for the outer member and extending co-axially with the inner member, cams on the hub to actuate said pistons, 75 means for conducting the compressed fluid to and from said valve, means for retarding the movement of the outer member, and means for shifting the valve.

5. The combination with independently 80 revoluble outer and inner members disposed to form a compressing chamber, of a fixed abutment on the outer member determining the ends of the compressing chamber, radial pistons mounted on the inner member and working in the compressing chamber, means for stopping the rotary movement of the outer member, and means for actuating the pistons inward and outward to pass the 85 abutment.

6. The combination with independently 90 revoluble outer and inner members disposed to form a fluid compressing chamber, of a fixed abutment on the outer member projecting into the compressing chamber and forming the ends thereof, radial pistons carried by the inner member and working in the compressing chamber, means for actuating the pistons to pass the abutment, and a valve having a plurality of ports to control the 95 pressure within and to and from the compressing chamber.

7. The combination with an outer revoluble member having a segmental compressing chamber and an inner member coöperating 105 with the outer member, of a plurality of pistons carried by the inner member and working in the compressing chamber, a valve to control the flow of compressed fluid to and from the compressing chamber, manual 110 means for shifting the valve to one position when the inner member serves to drive an internal combustion engine, and spring means to retract the valve to compressing position.

8. The combination of a source of fluid 115 pressure supply, rotary means to compress and maintain the fluid pressure supply, a revoluble sprocket member adapted for connection with an engine, a sliding member mounted on the sprocket member adapted to 120 engage with the rotary compressing means for transmission of the fluid pressure, fluid pressure actuated means for effecting such engagement, valve means for changing the flow of fluid pressure to and from the rotary 125 compressing means, and a planetary transmission means between the rotary creative means and the revoluble sprocket member.

9. In an attachment for automobiles, the combination of a source of compressed fluid, 130

- a standard, a rotary sprocket gear mounted on the standard, and adapted for connection with an engine, a set of planetary pinions carried by the rotary sprocket member, an 5 outer revoluble member mounted on the sprocket member and moving concentrically therewith, an inner revoluble member forming with the outer member a compressing chamber, a fixed pinion on the inner revoluble member, said fixed pinion being in mesh with the planetary pinions, an internal geared member in mesh with the planetary pinions, ratchet teeth on the internal geared member and adapted to engage with corresponding ratchet teeth on the outer and inner members, a valve to control ports of admission to the compressing chamber, manual means to operate the valve to admit the compressed fluid to drive the inner member, 10 spring means to retract the valve to admit a fluid medium to be compressed, and means for utilizing the compressed fluid to stop rotation of the outer revoluble member.
10. The combination with outer and inner rotary compressing means, of means for receiving the compressed fluid, means actuated by the compressed fluid to limit the 15 movement of the outer rotary compressing means, and means actuated by the compressed fluid to place the receiving means in communication with the outer rotary compressing means when in relatively stationary position.
11. The combination with outer and inner rotary compressing means, of means for receiving the compressed fluid, brake means actuated by the compressed fluid to prevent rotation of the outer rotary compressing means, a spring-actuated valve to control the flow of compressed fluid to the brake means, 20 said valve being actuated when the pressure falls below a predetermined amount, means actuated by the pressure to close the valve, and means actuated by the fluid pressure to place the receiving means in communication with the outer rotary compressing means when relatively stationary.
- In testimony whereof I hereunto affix my signature this 21st day of August, in the year 1918.

MOTOI FUJIURA.
